BEVERAGE CASE OR SIMILAR ARTICLE

Cohen D. Jones, Jr., Claxton, Ga.

Application December 5, 1949, Serial No. 6,420

Term of patent 3½ years

(Cl. D58—5)

To all whom it may concern:

Be it known that I, Cohen D. Jones, Jr., a citizen of the United States, residing at Claxton, in the county of Evans and State of Georgia, have invented a new, original, and ornamental Design for a Beverage Case or Similar Article, of which the following is a specification, reference being had to the accompanying drawing, forming part hereof.

In the drawing:

Fig. 1 is a perspective view of a beverage case or similar article showing my new design; and

Fig. 2 is a vertical section thereof.

I claim:

The ornamental design for a beverage case or similar article, as shown.
